COMBINATION TELEPHONE TRAY, LAMP, AND MEMORANDUM PAD

James Pat Whitaker, Sledge, Miss.

Application April 15, 1952, Serial No. 19,322

Term of patent 3½ years

(Cl. D26—14)

To all whom it may concern:

Be it known that I, James P. Whitaker, a citizen of the United States, residing at Sledge, in the county of Quitman and State of Mississippi, have invented a new, original, and ornamental Design for a Combination Telephone Tray, Lamp, and Memorandum Pad, of which the following is a specification, reference being had to the accompanying drawing, forming a part thereof.

In the drawing:

Figure 1 is a top perspective view of a combination telephone tray, lamp, and memorandum pad, showing my new design, the drawing of the device being shown in its closed position;

Figure 2 is a top perspective view, showing the drawer of the device in its open position;

Figures 3 and 4 are, respectively, front and side elevations.

I claim:

The ornamental design for a combination telephone tray, lamp, and memorandum pad, substantially as shown.

JAMES PAT WHITAKER.
